UNITED STATES PATENT OFFICE.

ALEXANDER P. MORROW, OF ELMIRA, NEW YORK.

DESIGN FOR A BICYCLE-HUB.

SPECIFICATION forming part of Design No. 32,233, dated February 13, 1900.

Application filed January 13, 1900. Serial No. 1,393. Term of patent 14 years.

To all whom it may concern:

Be it known that I, ALEXANDER P. MORROW, a citizen of the United States, residing at Elmira, in the county of Chemung and State 5 of New York, have invented and produced a new and original Design for Bicycle-Hubs; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention is a design for bicycle-hubs; and it consists of a hub having the shape and contour illustrated in the accompanying drawings, in which—

Figure 1 is a view in perspective of a hub 20 embodying the design. Fig. 2 is a side elevation of the same, and Fig. 3 is a perspective view taken from the end opposite to that shown in Fig. 1.

The reference-numeral 1 designates the cylindrical sleeve or body portion of the hub, 25 having adjacent to one end thereof a vertical flange 2, formed with an annular row of perforations 3.

4 designates an annular vertical flange projecting from the sleeve 1 and joined to a horizontal flange 5, overhanging the sleeve 1, and having its edge turned outward, forming an annular vertical rim 6. The point of junction between the vertical flange 4 and the horizontal flange 5 is rounded, as shown at 7, 30 and the sleeve 1 is extended beyond the vertical rim 6, concentric therewith, as shown at 8.

The leading features of my design are the annular vertical flange 4, the overhanging 40 horizontal flange 5, rounded at the point 7, and the annular vertical rim 6, together with the sleeve extension 8, concentric with said overhanging flange 5.

I claim—

45 The design for a bicycle-hub herein shown and described.

In testimony whereof I affix my signature in presence of two witnesses.

ALEXANDER P. MORROW.
